UNITED STATES PATENT OFFICE.

DAVID SPENCE, OF NORWALK, CONNECTICUT.

DESIGN FOR A TIRE-TREAD.

47,969.

Specification for Design.

Patented Oct. 12, 1915.

Application filed August 9, 1915. Serial No. 44,660. Term of patent 14 years.

To all whom it may concern:

Be it known that I, DAVID SPENCE, a subject of the King of Great Britain and Ireland, residing at Norwalk, in the county of Fairfield and State of Connecticut, have invented a new, original, and ornamental Design for a Tire-Tread, of which the following is a specification.

In the drawings, Figure 1 is a miniature perspective view of a tire embodying the design; Fig. 2 is a front elevation of a portion of the tire on an enlarged scale; and

Fig. 3 is a transverse section taken on the plane of the line *a—a* in Fig. 2.

I claim:

The ornamental design for a tire tread as shown.

In testimony whereof I affix my signature in presence of two witnesses.

DAVID SPENCE.

Witnesses:

C. OTIS FITCH,
H. C. RICHARDS.
